CLAIM

The ornamental design for a printer enclosure, as shown and described.

DESCRIPTION

FIG. 1 is an upper front perspective view of a first embodiment of the printer enclosure of the present invention, with the printer enclosure including shiftable panels that are transparent or translucent;

FIG. 2 is a front elevational view of the printer enclosure of the first embodiment;

FIG. 3 is a right side elevational view of the printer enclosure of the first embodiment;

FIG. 4 is a left side elevational view of the printer enclosure of the first embodiment;

FIG. 5 is a rear elevational view of the printer enclosure of the first embodiment;

FIG. 6 is a top view of the printer enclosure of the first embodiment;

FIG. 7 is an upper front perspective view of the printer enclosure of the first embodiment similar to FIG. 1, but showing shiftable panels of the printer enclosure opened to permit access to an interior of the printer enclosure;

FIG. 8 is a front elevational view of the printer enclosure of the first embodiment similar to FIG. 2, but showing the shiftable panels opened to permit access to the interior;

FIG. 9 is a right side elevational view of the printer enclosure of the first embodiment similar to FIG. 3, but showing the shiftable panels opened to permit access to the interior;

FIG. 10 is a left side elevational view of the printer enclosure of the first embodiment similar to FIG. 4, but showing the shiftable panels opened to permit access to the interior;

FIG. 11 is an upper front perspective view of a second embodiment of the printer enclosure of the present invention, with the printer enclosure including shiftable panels that are opaque;

FIG. 12 is a front elevational view of the printer enclosure of the second embodiment;

FIG. 13 is a right side elevational view of the printer enclosure of the second embodiment;

(Continued)

FIG. 14 is a left side elevational view of the printer enclosure of the second embodiment;
 FIG. 15 is a rear elevational view of the printer enclosure of the second embodiment;
 FIG. 16 is a top view of the printer enclosure of the second embodiment;
 FIG. 17 is an upper front perspective view of the printer enclosure of the second embodiment similar to FIG. 11, but showing shiftable panels of the printer enclosure opened to permit access to an interior of the printer enclosure;
 FIG. 18 is a front elevational view of the printer enclosure of the second embodiment similar to FIG. 12, but showing the shiftable panels opened to permit access to the interior;
 FIG. 19 is a right side elevational view of the printer enclosure of the second embodiment similar to FIG. 13, but showing the shiftable panels opened to permit access to the interior; and,
 FIG. 20 is a left side elevational view of the printer enclosure of the second embodiment similar to FIG. 14, but showing the shiftable panels opened to permit access to the interior. The broken lines shown in some of the figures show portions of the printer enclosure that form no part of the claimed design.
